SHOE

Joseph G. Zaher, Brooklyn, N. Y.

Application June 24, 1953, Serial No. 25,627

Term of patent 14 years

(CL. D7—7)

To all whom it may concern:

Be it known that I, Joseph G. Zaher, a citizen of the United States and a resident of Brooklyn, county of Kings, State of New York, have invented a new, original, and ornamental Design for a Shoe, of which the following is a specification, reference being had to the accompanying drawing, forming part hereof and in which:

Fig. 1 is a side elevational view of a shoe, showing my new design with the dominant features thereof illustrated in full lines.

Fig. 2 is a top elevational view of the shoe.

Fig. 3 is a front elevational view thereof.

My design is characterized by the arched shank of the outsole member extending under and merging with the heel member as shown.

I claim:

The ornamental design for a shoe, substantially as shown and described.
